United States Patent Office

Des. 192,525
Patented Apr. 3, 1962

192,525

LAP TRAY OR THE LIKE

Caleb L. Campbell, 5722 Euclid, Kansas City, Mo., and
Louie F. Redin, Weatherby Lake, Mo.

Filed Dec. 27, 1960, Ser. No. 63,335

Term of patent 7 years

(Cl. D44—10)

Fig. 2.

Fig. 3.

Fig. 1.

FIG. 1 is a side elevational view partly in section of a lap tray or the like, showing our new design; and

FIG. 2 is a top plan view thereof; and

FIG. 3 is an end elevational view thereof; and

FIG. 4 is an opposite end elevational view thereof.

We claim:

The ornamental design for a lap tray or the like, as shown.
